Filed Dec. 4, 1961, Ser. No. 67,799

Term of patent 14 years

(Cl. D54—2)

FIG. 1.

FIG. 2.

FIG. 4.

FIG. 1 is a front elevational view of a corner of a solar screen embodying my new design, the balance of the screen being like that shown and which corner continues to form the complete screen as indicated by the fragmentary edges.

FIG. 2 is a side elevational view thereof.

FIG. 3 is a rear elevational view thereof; and

FIG. 4 is a top plan view of the screen as shown in FIG. 1.

I claim:

The ornamental design for a solar screen, as shown and described.
